UNITED STATES PATENT OFFICE.

MICHAEL F. GORMAN, OF BINGHAMTON, NEW YORK.

AUTOMATIC FLATIRON LIFTER.

Application filed March 25, 1921. Serial No. 455,481.

To all whom it may concern:

Be it known that I, MICHAEL F. GORMAN, a citizen of the United States, and residing at Binghamton, in the county of Broome and State of New York, have invented certain new and useful Improvements in Automatic Flatiron Lifters, of which the following is a specification.

10 My invention relates to a support for pressing irons, the primary object thereof being the provision of a support of this character which is adapted to be freely suspended at all times, and in which the weight of the iron is taken up, so that a person using the same is relieved of all strain.

15 Another object is the provision of such a support, in which the iron is adapted to be freely moved in any and all directions without hindrance to the use of same.

20 With these and such other objects in view, as will be apparent from the description, my invention resides in a novel construction, combination and arrangement of parts, to be hereinafter described and claimed, and 25 illustrated in the accompanying drawings, in which like reference characters designate like parts.

Figure 1 is a vertical section partly in elevation of the preferred form of my invention assembled;

Figure 2 is an elevation thereof;

Figure 3 is an elevation of an element of the invention;

30 Figure 4 is a bottom plan view of the element illustrated in Figure 3;

Figure 5 is a horizontal section on line H—H of Figure 1;

Figure 6 is a vertical sectional view illustrating a modified form of the invention; 40 and

Figure 7 is an elevation illustrating a detail of the suspension means.

In the preferred form, the support is adapted to be suspended from the ceiling as 45 shown at 1, and in detail comprises the tubular body A provided at one end with a head 2 carrying a hook 3 adapted to be engaged with the supporting link 5 fastened in a hook 4 secured in the ceiling. The head 2 is provided with a reduced extension 6 extending inwardly of the body, and a cylindrical member 7 is slidably disposed within the body and carries a reduced extension 8 adjacent the head 2. Connecting 50 the head 2 and member 7 is a coil retractile spring 9 disposed within the body, and sur-

rounding the reduced extensions 6 and 8. The lower end of the body is provided with a cap 10 centrally apertured as at 11, to receive therethrough a rod 13 suspended by a 60 swivel 18 engaged with a hook 12 secured in the block 7.

The lower end of rod 13 extends beyond the body and is adapted to receive thereon the iron supporting member, in the form of 65 a sleeve 14, provided with a thumb screw 15 for adjustment to the rod, and carrying a pair of hook arms 17, mounted on a pivot pin 16 disposed in the outer end of the sleeve. The lower ends of arm 17 are bifurcated as 70 at 18 to engage the handle of a pressing iron C as illustrated in Figure 1.

In the modified form illustrated in Figure 6, a cylindrical casing is provided with a head 2' carrying a suspension hook 3 75 adapted to engage the suspension links hereinbefore described. Slidably mounted within the body D is a tubular body D' having in its upper end a head 2 provided with a reduced extension 6 extending inwardly of 80 the casing adapted to abut a similar reduced extension 8 carried on a cylindrical member 7 slidably disposed within the casing and connected with the head 2 by means of the coil retractile spring 9 surrounding the extensions 6 and 8. In this modified form, the lower end of the tubular casing D is open to permit the movement of the body therethrough, and the lower end of the body 85 is provided with a cap 10, apertured at 11, to receive therethrough the rod 13, swiveled to the hook 12 carried in the member 7. The casing D is provided with a longitudinal slot 19 in which is adapted to slide a set screw 20 carried by the head 2, whereby 90 the body D' may be slidably adjusted within the casing.

In Figure 7 I have illustrated an adjustable connecting member 5' in the link 5, whereby a further adjustment may be had 100 in the suspension means. Hooks 21 are provided on the lower end of the tubular body to form supports for the pressing iron C when not in use.

In the operation of my invention, the 105 hooks 17 are engaged with the handle of the pressing iron C whereby the iron will be yieldingly supported in any position desired. The swiveled connection between the rod 13 and the sliding member 7 permits the 110 free movement of the iron in any direction, while the resilient connection between the

members 7 and the head 2 of the body, provides at all times an elastic support. The link connection between the ceiling and the body as described, provides for a free suspension of the device, while the construction of the iron supporting member B with sleeve 14 provides an adjustable connection for the iron relative to the supporting rod 13.

The modified form illustrated in Figure 6 10 differs only in that a further adjustment is obtained between the body D and the casing D' by means of the connections described.

While I have described and illustrated in 15 the description and drawings certain details and materials which enter into the construction and operation of my invention, it is desired to be understood that I do not intend to limit myself to these but that any such may be used as will fall within the scope of the 20 invention as claimed.

I claim:

1. A support for pressing irons comprising a tubular body adapted for suspension and having its lower end closed and formed 25 with a central aperture, a cylindrical head fitted and secured within the upper end of the body, and having its lower portion reduced, a cylindrical block slidably mounted within the body and of a diameter only 30 slightly less than the internal diameter of the body so as to be guided by the body, the upper portion of the block being reduced, a coil spring surrounding the reduced portions of the head and block and connected 35 to the head and block for normally holding

the head retracted, a rod having its inner end swiveled to the lower face of the block and projected through and guided by the aperture in the body, and a pressing iron holder connected to the outer end of the rod. 40

2. A support for pressing irons comprising a tubular casing adapted for suspension having the upper end closed and the lower end open, the wall of the casing being provided with an elongated vertical slot, a 45 tubular body slidably arranged within the casing having the upper end open and the lower end closed and provided with a central aperture, a head seated on and secured to the upper edge of the body for closing 50 the same and provided with a reduced extension, a cylindrical block slidably arranged within and guided by the body having its upper portion provided with a reduced extension, a coil spring surrounding 55 and secured to the reduced extensions of the head and block for normally holding the block adjacent the head, an iron holder carrying rod slidably arranged in the aperture in the body and having its inner end 60 swivelly connected to the block, and a set screw having its shank arranged through the slot in the casing and anchored in the body and the head whereby the body may be releasably clamped in a position projecting 65 from the casing or else clamped to lie entirely within the casing substantially as and for the purposes set forth.

In testimony whereof I affix my signature.

MICHAEL F. GORMAN.
